(57) CLAIM

The ornamental design for a golf club head, as shown and described.

DESCRIPTION

FIG. 1 is a perspective view of a golf club head employing an ornamental design in accordance with the present invention;

FIG. 2 is a front elevational view of the golf club head of FIG. 1;

FIG. 3 is a rear elevational view of the golf club head of FIG. 1;

FIG. 4 is a right side elevational view of the golf club head of FIG. 1;

FIG. 5 is a left side elevational view of the golf club head of FIG. 1;

FIG. 6 is a top plan view of the golf club head of FIG. 1; and, FIG. 7 is a bottom plan view of the golf club head of FIG. 1.

The broken lines shown on the drawing are included for the purpose of illustrating unclaimed subject matter and forms no part of the claimed design.
